UNITED STATES PATENT OFFICE.

GEORGE W. FRENCH, JR., OF DANVERS, MASSACHUSETTS.

APPARATUS FOR GUIDING CLOTH.

1,268,956.

Specification of Letters Patent. Patented June 11, 1918.

Application filed September 8, 1914. Serial No. 860,539.

To all whom it may concern:

Be it known that I, GEORGE W. FRENCH, Jr., a citizen of the United States, and resident of Danvers in the county of Essex and State of Massachusetts, have invented certain new and useful Improvements in Apparatus for Guiding Cloth, of which the following is a specification.

The present invention relates to a device for guiding cloth in its passage to machines which are used for performing various operations upon the cloth in finishing the same. It is necessary when feeding cloth to such machines to feed it without wrinkles and in the proper direction and location. The object of my present invention is to provide a guiding and centering apparatus for acting upon cloth in the manner indicated, which is automatic in action and is controlled wholly by mechanical controlling means. The particular means or apparatus in which I have embodied my invention is fully described in the following specification and is illustrated in the accompanying drawings, in which I have shown diagrammatically the elements of mechanisms wherein I have embodied my invention.

In the drawings, Figure 1 is a plan view of a portion of a web of cloth and of the apparatus in which the invention is embodied.

Fig. 2 is a vertical section on line 2—2 of Fig. 1.

Fig. 3 is a side elevation of the apparatus. Figs. 4, 5, and 6, are respectively, a plan view, a side elevation, and a front elevation of a modified embodiment of the invention.

The same reference characters indicate the same parts in both figures.

Referring to the drawings *a* represents a web of cloth which is passed into a machine by which operations are to be performed on the cloth, from some container on, or in, which the cloth has been held. It is not

material to my invention what the nature of the machine may be to which the cloth passes nor what the container may be from which the cloth is taken. Such container may be a roll on which the cloth is wound, or a box or chamber in which the cloth has been laid and plaited, or it may be of any other character. The only point which is material to my invention is that, in passing from the container to the machine it is necessary that the cloth be guided with re-

spect to its position laterally and I have provided a simple mechanical means for so guiding the cloth. I have not illustrated the container from, or the machine to, which the cloth passes, or any part thereof, any further than to indicate at *b*, *b* and *c*, *c* in Fig. 3 two pairs of complemental feed rolls by which the cloth is propelled, and between which it is held in an extended condition.

The following described devices and mechanisms constitute my invention. The cloth passes between complemental guiding rolls *d*, *e* of which there is a set adjacent to each edge of the cloth web. The rolls *d* and *e* of each set or pair preferably have their axes parallel to one another and set at other than right angles to the length of the cloth. These rolls are turned by the friction of the cloth passing in contact with them, and their axes are at such an inclination with respect to the direction in which the cloth travels that those points of the rolls which are in contact with the cloth travel in a direction toward the adjacent edge of the cloth. The relation of the rolls to the cloth may be otherwise expressed by saying that the rolls are inclined inwardly and forwardly from the edges of the cloth, having respect to the direction of travel of the cloth. The result of this arrangement is that the rolls tend to pull one edge of the cloth away from the other edge, and thereby to hold the cloth smooth and prevent the formation of longitudinal wrinkles.

The lower roll (*e*) of each pair is movably mounted so that it may be withdrawn from the cloth and may cease to exert pressure thereon under certain conditions, hereinafter described. To this end the pivot stud *f* of said roll *e* (see Fig. 2) is pivoted to the supporting frame at the point *g*, to turn about an axis substantially parallel to the path in which the cloth travels, and is provided with or connected to a downwardly extending arm *h* which bears against a cam *i*. Said cam is here shown as being arranged in a horizontal plane and mounted to rotate about a vertical axis, although it may evidently be arranged in any other position in which it may perform the duties herein-after set forth. It preferably has a number of projections and depressions alternating with one another as shown in Fig. 1. Actuating means are provided for applying force tending to rotate the cam. One form

of means suitable for this purpose consists of a weight *j* connected to a cord *k* which passes around a drum *l* with which the cam *i* is connected. It is to be understood that this particular actuating means is representative of any mechanism which might be employed, and that various other mechanisms, including a spring motor, would equally well be used. I do not limit the invention to any particular actuating means, but consider that any mechanism which is always potentially operative but is adapted to be restrained from operation, is within the contemplation of my invention. This mechanism is normally prevented from moving the cam, by means consisting of an escape wheel *m*, which is connected to the drum *l*, and an escape lever or fork *n*. The escape lever is pivoted at *o* to the frame and has an arm *p* which is held yieldingly against the edge of the cloth web by a spring *q*. The fork has two fingers *r* and *s* which are adapted to obstruct alternately with the teeth of the escape wheel *m*. The arm *p* of the escape lever is a feeler and is controlled by the cloth web so as to cause the rolls *d* and *e* to guide the cloth. When the cloth is traveling in the proper path, as shown in Fig. 1, one of the projections or high points of the cam *i* bears against the lever *h* and holds the roll *e* in contact with the cloth. If now the cloth should be shifted to one side out of its proper path, the feeler *p* at the side toward which it shifts is moved, and displaces the finger *r* from in front of that tooth of the escape wheel with which it had previously been engaged, and at the same time places the finger *s* in a notch between two of the teeth of said wheel. Thereupon the wheel is allowed to turn under the influence of the actuator weight *j* until arrested by the finger *s*. The teeth of the wheel *m* are so spaced that the angular movement thus permitted to the cam is sufficient to bring a low point of the cam adjacent to the arm *h*, whereupon the roll *e* drops and becomes inoperative to guide the cloth. This leaves the guide rolls at the opposite edge of the cloth alone to be in operation, and these latter pull the cloth laterally in the opposite direction to its first displacement until the feeler is allowed to move under the pressure of spring *q* far enough to disengage the finger *s* from the tooth of escape wheel *m* with which it is engaged and bring the finger *r* into the path of the tooth next to that with which said finger *r* was previously engaged. Thereupon another high part of the cam is brought into action upon the lever *h* and the roll *e* is raised and put into operation again.

Thus it will be seen that whenever the cloth is shifted to either side of the path in which it should travel the guide rolls on

the side toward which it is displaced are put out of action, and only the guide rolls on the opposite side of the web are left operative. Thereupon the operative guide rolls become able to shift the web back to its proper path; and when it has reached the path the rolls on the side toward which it was first displaced are again rendered operative.

The construction shown in Figs. 4, 5, and 6 involves two rolls *d'* and *e'* arranged to act on opposite faces of the web of cloth *a* adjacent to the edge thereof, in the same manner already described. The roll *e'* is carried by a swing frame or holder *f'* which is pivoted at one side of the roll on a stud *g'* which is supported rigidly by any desired character of frame work. The roll carrying frame *f'* is provided with a downwardly extending arm equipped with a contact piece or toe *h'* which coacts with a cam *i'*, the latter being loosely mounted on a shaft *8*, which is preferably parallel to the axes of the rolls *d'* and *e'*.

The feeler or control lever *p'* is pivoted on a stud *o'* suitably supported in proper relation to the other parts of the apparatus and has an upstanding arm crossing the plane of the cloth and held toward the adjacent edge thereof by a spring *q'*. The feeler has another arm formed with a fork *r'*, *s'* which straddles a clutch *z* splined upon the shaft *8*, and is connected by means of pins *2* or *3* with a collar or strap *y* surrounding the clutch. The collar is contained between shoulders on the clutch so that it may move the clutch axially and permit the clutch to rotate when in any position, in a well known manner. The clutch *z* has a projection *10* adapted to enter a notch *11* in a complementary clutch member *x* which is fast to the cam *i'* and loose on shaft *8*. Shaft *8* is rotated whenever the rolls *d'* and *e'* rotate, by means of a gear *v* on shaft *8*, which meshes with an idler gear *u* mounted on the opposite side of the frame work from the roll *e'*, and being in mesh with a gear *t* on the shaft of roll *d'*. The cam *i'* has an abrupt shoulder *4* and its surface is otherwise continuous and without abrupt offsets. Such surface provides a gradual rise from the bottom of the shoulder *4* through a small proportion of the circumference of the cam to about the point *12*, and from that point to the outer limit of the shoulder the surface of the cam is approximately concentric with the shaft *8*. A weight *w* is connected with the cam in such a way as normally to hold the high part of the cam in contact with the contact toe *h'* of the swing frame *f'*, when the cam is not otherwise prevented from assuming this position, whereby the roll *e'* is pressed against the under side of the cloth.

It is to be understood that the mechanism

or device last described is duplicated at each edge of the cloth web in the same way that the device of Figs. 1, 2, and 3 is duplicated, as shown in Fig. 1.

5 The operation of this device may now be understood. When the cloth web is displaced too far to one side or the other so that it shifts the feeler p' at the side toward which it is displaced, such feeler engages the clutch z with the clutch x , causing the cam i' to be rotated until the shoulder 4 passes the contact toe h' . Then the roll e' drops and releases the cloth, which is free to be shifted in the opposite direction by the 15 guiding rolls at the opposite edge of the web. The clutch members x and z then cease to rotate because, with the pressure of roll e' removed, the friction of the cloth on the roll d' is insufficient to turn such roll, and the driving force for the clutch members then ceases to operate. The contact member h' and cam shoulder 4 are relatively so arranged with respect to the weight w that when the shoulder 4 has passed the 25 point h' , as described, the weight w is carried just beyond a position above the axis of shaft 8, so that it tends to fall into the normal position. It is restrained from thus falling, however, by a pin 5, which projects 30 from the collar y into the path of the weight when clutch z is engaged with the clutch x . Now when the cloth recedes, it is followed by the feeler p' , acted on by spring q' , until the cloth reaches its normal middle position, 35 when the clutch z has been so far withdrawn as to disengage the clutch x and release the weight w . Then the weight is allowed to fall and turn the cam i' far enough to bring the roll e' into engagement with the cloth, 40 whereupon the rolls resume their normal function of guiding the cloth and holding it smooth.

It will be seen that the mechanism which I have provided for accomplishing the effect 45 above described is entirely mechanical and that it is simple and efficient. I do not by any means limit the invention to the particular forms of mechanism here shown as I consider that any apparatus however constructed in which cam means, or any other means corresponding to the terms of the claims, are employed for making the guide rolls alternately operative and inoperative under the control of a mechanical actuator 55 and of a feeler controlled by the cloth is within the scope of my invention. In explanation of the terms "horizontal" and "vertical" herein used, it should be understood that these terms are not absolute but 60 are relative and relate to the direction in which the cloth travels. Thus in the present drawings the cloth is horizontal and travels in a horizontal line and the lines and directions which are perpendicular to the cloth and to its direction of travel are ver-

tical, but the mechanism and the principles of its operation will be the same if the cloth were arranged in any other plane and traveled in any other direction. Consequently the term "horizontal" may be defined as 70 meaning in or parallel to the plane of the cloth or to the direction of travel of the cloth, and "vertical" may be defined as perpendicular to such plane or such direction.

What I claim and desire to secure by Letters Patent is:

1. An apparatus for guiding cloth comprising guide rolls at an inclination to the direction of travel of the cloth and arranged to grasp the cloth between them, a cam arranged to act upon one of said rolls and operative according to its position to place the said roll against the cloth and away from the same respectively, an actuator tending constantly to move said cam, a feeler engaging the edge of the cloth, and an escape mechanism operated by said feeler and constructed to permit and limit actuation of the cam upon each operation to an extent such as to bring said roll from one 90 of said positions to the other.

2. In an apparatus for feeding and guiding cloth, the combination with pairs of rolls through which the cloth passes, one of the rolls of each pair being capable of withdrawal from the cloth, a cam arranged to act on said roll and shift the same from operative to inoperative position and the reverse, a potentially operative actuator for said cam, and an escape mechanism controlled as to its operation by displacement of the cloth constructed and arranged to permit, at each operation thereof, the displacement of said roll from one of its extreme positions to the other.

3. In an apparatus for feeding and guiding cloth the combination of a pair of rolls between which the cloth passes arranged at an inclination to the line of travel of the cloth, a feeler bearing against an edge of the cloth, and movable in consequence of lateral displacement of such edge and mechanical means controlled by said feeler when the latter moves in one direction for causing displacement of one of said rolls from contact with the cloth, and for causing return of said roll against the cloth when the feeler is moved in the opposite direction.

4. An apparatus for guiding cloth comprising complementary pressure rolls having 120 their axes parallel, one of said rolls being movable toward and away from the other, a cam having alternating protuberances and depressions for so moving said roll, a potentially active actuator for said cam, an escape device for said cam constructed to permit a step by step rotation of the cam in such relation as to bring the protuberant and depressed portions thereof alternately into action upon the roll, and a feeler arranged 130

to engage the edge of a web of cloth passing through said rolls for controlling said escape device.

5. In an apparatus for feeding and guiding cloth, the combination of complemental rolls gripping the edge portion of the cloth and having their axes inclined to the direction of travel of the cloth, one of said rolls being movable away from the other, a device for converting rotary into reciprocating motion arranged to act on said movable roll, an actuator tending to rotate said device, an escape mechanism for permitting limited movements of said actuator, and a feeler engaged with the edge of the cloth for operating said escape mechanism according to the lateral position of the cloth.

6. In an apparatus for feeding and guiding cloth, the combination of complemental rolls gripping the edge portion of the cloth and having their axes inclined to the direction of travel of the cloth, one of said rolls being movable away from the other, a device for converting rotary into reciprocating motion arranged to act on said movable roll, and constructed to occupy different positions, in one of which it causes the said movable roll to bear on the cloth, and in another of which it causes removal of said roll from the cloth, an actuator tending to rotate said device, and an escape mechanism for permitting limited movements of said actuator sufficient to cause rotation of said device from one into another of its different positions.

7. In an apparatus for feeding and guiding cloth, the combination of complemental rolls gripping the edge portion of the cloth and having their axes inclined to the direction of travel of the cloth, one of said rolls being movable away from the other, a rotary device arranged to act on said movable roll, rotatable into different positions and constructed to cause said roll to bear on the cloth or to be removed therefrom according to its position, and an intermittently operating actuator controlled by the lateral position of the cloth for rotating said device from one to another of its positions.

8. In an apparatus for feeding and guiding cloth, the combination of complemental guiding rolls gripping the edge portion of the cloth, one of which is movable toward and

away from the surface of the cloth against which it is arranged to act, a cam for controlling such movements of said movable roll, and means controlled by shifting the cloth transversely of its direction of normal motion, for causing actuation of said cam.

9. In a cloth guiding apparatus the combination with gripping guiding rolls, one of which is removable from the path in which the cloth travels, a rotatably movable device acting upon said roll to hold the latter against the cloth when in one of its positions, and constructed so as to permit withdrawal of the roll when in another position, impelling means tending to move said device from one position to another, and a feeler adapted to be engaged by the cloth and to be shifted thereby for enabling said means to become operative when the cloth occupies a certain position.

10. In a cloth guiding apparatus complemental guiding rolls between which the cloth is passed, one of said rolls being movable toward and away from the cloth and being constantly urged by gravity away from the cloth, a rotatable cam arranged to act on said roll and constructed to hold said roll against the cloth when in one of its positions, and to permit withdrawal of the roll when in another position, and means controlled in its operation by the position of the traveling cloth for causing said cam to shift from one to another of its said positions.

11. In a cloth guiding apparatus complemental cloth-engaging and guiding rolls, one of which is movable away from the cloth and is constantly urged by gravity away from the cloth, a rotatable device for acting upon said roll constructed so as when in one position to permit such withdrawal of the movable roll and when in another position to put said roll into engagement with the cloth, constantly acting impelling means tending to move said device from one of said aforesaid positions to the other, and a feeler device engaging and moved by the cloth for controlling the operation of said means.

In testimony whereof I have affixed my signature, in presence of two witnesses.
